AUTOMATIC ELECTRIC CIRCULATION
HEATER FOR AUTOMOBILES

John R. McClain, Wooster, Ohio

Application December 9, 1949, Serial No. 132,003

5 Claims. (Cl. 219—38)

1

The invention relates to heaters for the circulating cooling fluid in automobile motors and radiators, and more particularly to an automatic, electric, thermostatically controlled heater.

It is an object of the invention to provide a simple, economic heater which may be quickly and easily mounted in the hose line between the lower end of the radiator and the water pump of the motor.

Another object is to provide such a heater which is easily adapted for installation upon the motor of any automobile.

A further object is to provide a heater of this character which is automatically and thermostatically controlled.

A still further object is to provide such a heater which is easily adjustable to maintain the desired temperature.

The above objects together with others which will be apparent from the drawing and following description or which may be later referred to, may be attained by constructing the improved heater in the manner hereinafter described in detail and illustrated in the accompanying drawing, in which:

Figure 1 is a fragmentary, side elevation, on a small scale, showing the radiator and a portion of the motor of an automobile with the improved heater mounted in the hose line between the lower end of the radiator and the water pump;

Fig. 2 is a side elevation of the improved heater, showing the same actual size; and

Fig. 3 a longitudinal, sectional view through the heater, showing the heating unit therein.

Referring now more particularly to the embodiment of the invention illustrated in the drawing, in which similar numerals refer to similar parts throughout the several views, a portion of an automobile engine block is shown at 10, with the corresponding portion of the cylinder head indicated at 11, the water pump 12 being mounted upon the front of the engine block.

The radiator is shown at 13, the upper portion thereof being connected by the usual flexible hose 14 to the cylinder head 11 and the lower end thereof being connected by a flexible hose 15 to the water pump 12.

The improved heater to which the invention pertains, is indicated generally at 16, and as shown in Fig. 1 is installed in the hose line 15, between the lower end of the radiator and the water pump. This heater comprises a cylindrical casing, preferably formed of two similar halves 17 having interlocking meeting edges 18 which

may be sweated or otherwise rigidly connected together.

Each cylindrical section 17 of the casing terminates outwardly in a frusto-conical portion 19 upon which a reduced neck 20 is formed. The meeting edges of the cylindrical sections 17 have spaced pairs of half-round notches 21 therein to accommodate the terminal posts 22 which are located through and brazed or otherwise rigidly connected within these notches and are attached to opposite ends of the heating element 23. This heating element may be any conventional heating unit, preferably double protected by being sealed in magnesium oxide covered with a non-corrosive copper sheath. No claim is made to this particular type of heating element, which is obtainable upon the market.

A thermostat, which is also of conventional construction and obtainable upon the market, is indicated generally at 24, and is mounted upon the cylindrical casing 17—17, preferably by bending the terminal ears 25 thereof angularly, as shown in the drawing, and brazing or otherwise connecting them to the frusto-conical portions 19 of the casing.

An adjusting screw 26 is provided upon the thermostat for adjusting the temperature control, and a pair of terminal posts 27 are provided upon the thermostat.

To install the improved heater in an automobile, truck, bus, tractor, or stationary engine, an intermediate section of the flexible hose 15 is removed and the ends of the remaining portions of this hose are slipped over the reduced necks 20 of the heater casing, and clamped thereon as indicated at 28 in Fig. 1.

One terminal post 22, of the heating unit, is connected to one terminal post 27 of the thermostat, as by a wire 29. Wires 30 and 31 connect the other terminal post 22 of the heating unit and the other terminal post 27 of the thermostat respectively to a receptacle 32, which may be mounted at some convenient position upon the car outside of the hood, preferably upon the apron just back of the front bumper.

In order to operate the heater, an extension cord 33, connected to a 110 v. A. C. or D. C. current outlet, and provided with a conventional connection plug 34, is plugged into the receptacle 32 as indicated in Fig. 1.

The heating unit 23 is thus activated, heating the water or other cooling fluid in the circulating system of the radiator and water jacket of the motor, the temperature being automatically controlled by the thermostat, thus not only protecting

the motor and radiator from freezing, but guaranteeing dependable quick starting of the motor in the coldest weather, regardless of the length of time the car may have been standing, assuring heating of the inside of the car with the hot water heater much quicker than under ordinary circumstances and greatly prolonging the life of the battery.

All parts of the improved heater are formed of brass, copper or other non-corrosive material so 10 that the same is completely rust-resistant.

I claim:

1. As an article of manufacture, a heater for the cooling fluid in internal combustion engines and radiators therefor, provided with a hose connecting the radiator and the water jacket of the engine, said heater comprising a cylindrical casing, means at each end of the casing for insertion into said hose, a heating element of coil type located within the cylindrical casing, a non-corrosive metal sheath covering the heating element coil, insulation surrounding the heating element coil and sealed within said non-corrosive sheath, conductor means connected to opposite ends of the heating element coil, and an electric receptacle connected to said conductor means and located at a point spaced from the engine, whereby a 110 volt source of electric power may be detachably connected to said heating element coil through said receptacle. 15 20

2. As an article of manufacture, a heater for the cooling fluid in internal combustion engines and radiators therefor, provided with a hose connecting the radiator and the water jacket of the engine, said heater comprising a cylindrical casing, means at each end of the casing for insertion into said hose, a heating element of coil type located within the cylindrical casing, a non-corrosive metal sheath covering the heating element coil, insulation surrounding the heating element coil and sealed within said non-corrosive sheath, a thermostat associated with the casing, conductor means connecting one end of the heating element coil to one side of the thermostat, conductor means connected to the opposite end of the heating element coil and the opposite side of the thermostat, and an electric receptacle connected to said last named conductor means and located at a point spaced from the engine, whereby a 110 volt source of electric power may be detachably connected to said heating element coil through 35 40 50 said thermostat and said receptacle.

3. As an article of manufacture, a heater for the cooling fluid in internal combustion engines and radiators therefor, provided with a hose connecting the radiator and the water jacket of the engine, said heater comprising a cylindrical casing, said casing comprising two similar cylindrical sections having shouldered, interlocking meeting edges rigidly connected together, means at each end of the casing for insertion into said hose, a heating element of coil type located within the cylindrical casing, a non-corrosive metal sheath covering the heating element coil, insulation surrounding the heating element coil and sealed within said non-corrosive sheath, conductor means connected to opposite ends of the 55 60 65

heating element coil, and an electric receptacle connected to said conductor means and located at a point spaced from the engine, whereby a 110 volt source of electric power may be detachably connected to said heating element coil through said receptacle.

4. As an article of manufacture, a heater for the cooling fluid in internal combustion engines and radiators therefor, provided with a hose connecting the radiator and the water jacket of the engine, said heater comprising a cylindrical casing, said casing comprising two similar cylindrical sections having shouldered, interlocking meeting edges rigidly connected together, means at each end of the casing for insertion into said hose, a heating element of coil type located within the cylindrical casing, a non-corrosive metal sheath covering the heating element coil, insulation surrounding the heating element coil and sealed within said non-corrosive sheath, a thermostat associated with the casing, conductor means connecting one end of the heating element coil to one side of the thermostat, conductor means connected to the opposite end of the heating element coil and the opposite side of the thermostat, and an electric receptacle connected to said last named conductor means and located at a point spaced from the engine, whereby a 110 volt source of electric power may be detachably connected to said heating element coil through said thermostat and said receptacle.

5. As an article of manufacture, a heater for the cooling fluid in internal combustion engines and radiators therefor, provided with a hose connecting the radiator and the water jacket of the engine, said heater comprising a cylindrical casing having a reduced neck at each end of the casing for insertion into said hose, a heating element of coil type located within the cylindrical casing, a non-corrosive metal sheath covering the heating element coil, insulation surrounding the heating element coil and sealed within said non-corrosive sheath, a thermostat associated with the casing, conductor means connecting one end of the heating element coil to one side of the thermostat, conductor means connected to the opposite end of the heating element coil and the opposite side of the thermostat, and an electric receptacle connected to said last named conductor means and located at a point spaced from the engine, whereby a 110 volt source of electric power may be detachably connected to said heating element coil through said thermostat and said receptacle.
